SWITCHING TYPE CONVEYER

Kenneth H. Hansen, White Plains, N. Y., assignor
to Cutler-Hammer, Inc., Milwaukee, Wis., a
corporation of Delaware

Application March 13, 1947, Serial No. 734,373

13 Claims. (Cl. 198—165)

1

This invention relates to conveyor systems for newspapers and other articles, and more particularly to systems affording switching.

In the application of Warren Bacon and Kenneth H. Hansen, Serial No. 730,012, filed February 21, 1947, now Patent No. 2,593,242, issued April 15, 1952, there is disclosed an improved conveyor switch which among other things provides for the transfer of a stream of papers from either of two separate conveyors, selectively, to a common conveyor. The present invention has among its objects, to provide through modification of such system with a minimum of alteration, one for transferring a single paper stream, selectively, to either of two separate conveyors, as for example, to convey paper from a single folder to either of two separate delivery tables.

Another object is to provide for continuous positive movement of the paper stream throughout its transfer to one or the other of said two separate conveyors.

Another object is to provide for derivation from the conveyor making delivery to the switching means, driving power for the switching means and the conveyor to which transfer is to be made.

Another object is to provide for rendering the establishment of driving connections to the selected conveyor concurrent with the positioning of the switching means to select the conveyor to which transfer is to be made.

Other objects and advantages of the invention will hereinafter appear.

In order that the invention may be more clearly understood, a conveyor system incorporating the invention will now be described, reference being made to the accompanying drawings, and it being understood that the system shown is susceptible of modification without departing from the scope of the appended claims.

In the drawings,

Figure 1 is a diagrammatic showing of coordination of a switch with a single folder and two separate delivery tables, the elements being shown only in outline;

Fig. 2 is a more or less schematic view showing in some detail the switch and portions of the system adjacent the switch;

Fig. 3 is like Fig. 2, but shows the switch in a different operating position;

Fig. 4 is a more or less schematic showing of the switch and that portion of the conveyor system shown in Figs. 2 and 3 viewed at right angles thereto and showing the conveyor drive transfer and shift mechanism and the conveyor pulley and belt arrangement;

2

Fig. 5 is in general similar to Figs. 2 and 3 but omitting the conveyor belts and showing driving connections, and

Fig. 6 is a more or less schematic showing of the shift mechanism for the conveyor drive transfer mechanism shown in Fig. 4 but viewed at right angles thereto.

Referring to Figure 1, it shows a stream of papers 1 to be delivered from a single press folder 2 selectively, to either of two separate delivery tables 3 and 4. When folder 2 is operating, stream 1 is to be conveyed by a conveyor 5 into a conveyor switch unit 6 for transfer to conveyor 7 which extends from the switch to delivery table 3 or to conveyor 8 which extends from the switch to delivery table 4. As will later be explained the switching means comprising switch unit 6 not only provides for the selective transfer of the paper stream to one of two delivery tables but concurrently provides for the transfer of driving power for conveyor 5 to the conveyor making delivery to the selected delivery table.

Referring to Fig. 2, it shows the belt and pulley arrangement of switch unit 6 and of conveyors 5, 7 and 9 adjacent to switch unit 6. When switch unit 6 is in the operating condition shown it will transfer papers from conveyor 5 to conveyor 7 when folder 2 is operating. Conveyor 5 has end pulleys in the switch unit 6. Conveyor 7 originates at a section joint 9 adjacent to and at the right of switch unit 6. Section joint 9 per se is not a part of the instant invention, but as will later appear its use simplifies the switching combination and is in this instance provided with an additional pulley forming part of the switching means. It will be apparent to those skilled in the art that the mechanism of section joint 9 can be incorporated in the switch unit if desired.

Conveyor 5 comprises belts 10 and 11 running on respective end pulleys 12^a and 13^a fixed respectively on shafts 12 and 13 carried by switch unit 6. A belt 14 runs on a pulley 12^b fixed on shaft 12 within switch unit 6 and on a free running pulley 15^a on shaft 15 carried by section joint 9. A divertible belt 16 runs on a pulley 17^a fixed on shaft 17 carried by section joint 9 and on a free running pulley 18^a on a short shaft 18 carried by an arm 19 rigidly fixed to a shaft 20 carried by the switch unit 6. Conveyor 7 comprises belts 21 and 22 running respectively on pulleys 15^b and 17^b fixed on shafts 15 and 17 of section joint 9. A belt 23 within switch unit 6 runs on a pulley 13^b fixed on shaft 13 and on a free running pulley 24^a on shaft 24.

When arm 19 is positioned as shown, the belt

3

16 is positioned in a cooperating relation with belt 14 and belt 14 with belts 16 and 11 form a transfer section through the switch unit 6 from conveyor 5. As will later appear, shafts 12, 15, 17 and 24 derive driving power from shafts 13 of conveyor 5.

Also as shown in Fig. 2, the switching means comprises additional pulleys, belts and shafts, the same being idle under the condition just described. Shaft 24 carries an end pulley for belt 25 of conveyor 8 and the switch unit has an additional shaft 26 carrying an end pulley for belt 27 of conveyor 8. The section joint 9 carries a swinging frame 9^a supporting a shaft 28 having a free running pulley 28^a on which runs a belt 29. The belts 25, 27, and 29 here shown in broken lines are more fully shown in Fig. 3 now to be described.

Referring to Fig. 3, it shows the switch unit in an operating condition to provide for the transfer of paper stream 1 from conveyor 5 to conveyor 8 when folder 2 is operating. Conveyor 8 as aforementioned comprises belts 25 and 27 which run on respective end pulleys 24^b and 26^a fixed on shafts 24 and 26. Belt 29 as aforementioned runs on a free running pulley 28^a and additionally it runs on a second free running pulley 18^b on the short shaft 18, and on a driving pulley 26^b on shaft 26. Belt 29 also bears against a free running pulley 24^c on shaft 24 whenever there is an absence of flow of papers through the switch unit to conveyor 8. Belts 10, 11, 14 and 23 respectively function as described in connection with Fig. 2. Belts 16, 21 and 22 (shown as broken lines) are idle and shafts 15 and 17 are idle.

When arm 19 is positioned as shown in Fig. 3 the belt 29 is positioned in a cooperating relation with belts 23 and 25 to form a transfer section through the switch unit 6 and provides for conveyance of the paper stream 1 from belts 11 and 14 to belts 25 and 27 of conveyor 8. As will later appear shafts 24 and 26 derive driving power from shaft 13 of conveyor 5.

Referring to Fig. 4, it shows in plan the various belts, pulleys and the belt shifting arm 19, described in connection with Figs. 2 and 3. Only one set of belts and associated pulleys and only one belt shifting arm are shown, but as will be apparent to those skilled in the art they are representative of a plurality of such belts, pulleys and belt shifting arms which in practice are suitably plural and spaced across the path of the paper stream to be handled. The belts are assumed to be of the usual coiled wire type.

Figs. 4, 5 and 6 considered together will afford an understanding of the driving connections of conveyors 5, 7 and 8 with the switch unit 6, the power drive shift mechanism in the switch unit for selectively transferring the driving power from conveyor 5 to conveyors 7 and 8, and also of the power means provided to change the operating condition of the switch unit.

Conveyor 5 has a chain 30 which drives a sprocket wheel 13^c fixed on shaft 13. Meshing gears 13^d and 12^c are fixed on their respective shafts 13 and 12. A second gear 13^e fixed on shaft 13 is provided for selectively transferring the power drive from shaft 13 to a gear 31^a fixed on a short shaft 31 carried by the switch unit or to a gear 24^d fixed on shaft 24, through the medium of two shiftable idler pinions 32 and 33 which are in continuous meshing engagement with gear 13^e. As will later appear, pinion 32 can be shifted to effect a meshing engagement

5 with gear 31^a thereby affording a transfer of power from shaft 13 to shaft 31, and pinion 33 can be shifted to effect a meshing engagement with gear 24^d thereby affording a transfer of power from shaft 13 to shaft 24.

A chain 34 driven by a sprocket wheel 31^b fixed on shaft 31 drives a corresponding sprocket wheel 17^c fixed on shaft 17 of section joint 9. A gear 17^d fixed on shaft 17 meshes with a gear 15^c fixed on shaft 15 and thus provides for the simultaneous drive of shaft 15. When driven, shafts 15 and 17 provide the drive for conveyor 7. A chain 35 driven by a sprocket wheel 17^e fixed on shaft 17 may be provided for transferring power to drive the run out mechanism of delivery table 3, or if conveyor 7 is of relatively extended length to provide the drive for successive sections of conveyor 7 in a well known manner. A gear 24^e fixed on shaft 24 meshes with a gear 26^c fixed on shaft 26 and thus provides for the simultaneous drive of shaft 26. When driven, shafts 24 and 26 provide the drive for conveyor 8. A chain 36 driven by a sprocket wheel 24^f fixed on shaft 24 may be provided for transferring power to drive the run out mechanism of delivery table 4, or if conveyor 8 is of relatively extended length to provide the drive for successive sections of conveyor 8 in a well known manner.

The aforementioned idler pinion 32 runs freely on a short shaft 37 by which it is supported in meshing engagement with the gear 13^e. Shaft 37 is disposed through and between arms 38^a of a pair of bell crank levers 38 (Figs. 4 and 6). Each of the levers 38 is pivotally supported by shaft 13 and they are disposed on opposite sides of the gear 13^e. The levers are connected together in a fixed relationship by the shaft 37 and by an additional suitable connection 38^b disposed through and between the arms 38^c, thereby providing for concurrent pivotal movement of said levers. Similarly, pinion 33 runs freely on a short shaft 39 by which it is supported in meshing engagement with gear 13^e. Shaft 39 is disposed through and between arms 40^a of a pair of bell crank levers 40. Each of the levers 40 is pivotally supported by shaft 13 and they are disposed on opposite sides of gear 13^e between one of the pair of levers 38 and gear 13^e. The levers are connected together in a fixed relationship by the shaft 39 and by an additional suitable connection 40^b disposed through and between the arms 40^c, thereby providing for concurrent movement of said levers. A crank rod 41 connects one of the levers 38 with a crank lever 42 fixed on shaft 20. A second crank rod 43 connects one of the levers 40 with a second crank lever 44 which is fixed on shaft 20 adjacent to the crank lever 42. As will be understood the crank rods 41 and 43 and crank levers 42 and 44 provide for the pivotal movement of the pairs of levers 38 and 40 about the shaft 13 when the shaft 20 is rotated.

Referring particularly to Fig. 6, it shows the aforementioned elements of the power drive shift mechanism in the switch unit 6 in two operating positions corresponding to the two operating conditions of said switch unit. The full line showing of these elements depicts their positions when switch unit 6 is in the operating condition shown in Fig. 3. Pinion 33 is in meshing engagement with gears 13^e and 24^d and thereby provides for the drive of the gear 24^d when shaft 13 is rotating. Pinion 32 is out of engagement with gear 31^a and therefore shaft 31 will be idle. When

the shaft 20 is rotated counterclockwise a predetermined amount, the bell crank levers 38 and 40, the pinions 32 and 33, the crank rods 41 and 43, and the crank levers 42 and 44 assume the positions shown in broken lines, which corresponds to the operating condition of the switch shown in Fig. 2. Pinion 32 is in meshing engagement with gears 13^e and 31^e and thereby provides for the drive of gear 31^e whenever shaft 13 is rotating. Pinion 33 is out of engagement with the gear 24^d and therefore shaft 24 will be idle.

Referring particularly to Figs. 4 and 5, an electric motor 45 is provided in switch unit 6 as a means of shifting the conveyor switch from one operating position to the other. Motor 45 is mounted in a suitable manner so that its rotor shaft 45^a is in a coplanar relationship with shaft 20. A pinion 45^b fixed on shaft 45^a meshes with a gear 20^a fixed on shaft 20. Motor 45 can be controlled in a suitable manner to run in reverse directions between fixed limits so as to position the arm 19 in either of the two positions shown in Figs. 2 and 3 and simultaneously position the pinions 32 and 33 in the two positions shown in Fig. 6. It is apparent that the shaft 20 can be rotated by manual means, as by a crank or lever to position arm 19 and pinions 32 and 33 in either of the two operating positions.

Referring to Figs. 2, 4, 5 and 6, when folder 2 is operating and it is desired to convey stream 1 to conveyor table 3 switch unit 6 is conditioned as shown in Fig. 2 and the drive for conveyor 7 through switch unit 6 becomes effective. Chain 30 will drive the sprocket 13^e in the clockwise direction and cause the shaft 13 to rotate in the same direction. Adjacent portions of belts 10 and 11 of conveyor 5 will therefore carry stream 1 into switch unit 6 where it is carried by a fixed transfer section comprising adjacent portions of belts 11 and 14. Shaft 31 will rotate in the clockwise direction, being driven by gear 13^e through pinion 32 and gear 31^e, and the chain 34 is driven by sprocket 31^b and in turn drives sprocket 17^e in the same direction. Adjacent portions of the belts 14 and 16 therefore carry stream 1 from the aforementioned fixed transfer section in switch unit 6 to the section joint 9. Shaft 15 rotates in the counterclockwise direction through the drive by gear 17^d of the gear 15^e. Adjacent portions of the belts 21 and 22 of conveyor 7 will therefore carry the stream 1 to the conveyor table 3. Belts 25 and 27 will be idle as shaft 24 will not be rotating.

Referring to Figs. 3, 4, 5 and 6, when folder 2 is operating and it is desired to carry stream 1 to conveyor table 4 switch unit 6 is conditioned as shown in Fig. 3 and the drive for conveyor 8 through switch unit 6 becomes effective. Chain 30 will drive sprocket 13^e in the clockwise direction and cause shaft 13 to rotate in the same direction. Adjacent portions of belts 10 and 11 will therefore carry stream 1 into switch unit 6 where it is carried by the aforementioned transfer section comprising adjacent portions of belts 11 and 14. Shaft 24 will rotate in the clockwise direction, being driven by gear 13^e through pinion 33 and gear 24^d and shaft 26 rotates in the counterclockwise direction through the drive of the gear 26^e by the gear 24^e. The sprocket 24^e drives the chain 36 of conveyor 8. Therefore, adjacent portions of belts 23 and 29 and of belts 25 and 29 will carry stream 1 from the transfer section comprising belts 11 and 14 to the belts 25 and 27 of conveyor 8. Chain 34 will be idle

as shaft 31 will not be rotating. Therefore belt 16 and belts 21 and 22 of conveyor 7 will be idle.

Preferred forms of supporting frame work for switch unit 6 and section joint 9 are shown schematically in Figs. 2, 3, 4 and 5. The frame of switch unit 6 comprises the shaft bearing side members 6^a, 6^b and 6^c which are held in a fixed parallel relationship with one another as by plurality of perpendicular struts 6^d and 6^e. Similarly, the frame of section joint 9 comprises shaft bearing side members 9^a and 9^b which are held in a rigid parallel relationship with one another as by a plurality of perpendicular struts 9^c.

What I claim as new and desire to secure by Letters Patent is:

1. The combination with a plurality of conveyor sections of the pulley and belt type and comprising a driven first section and second and third sections to be placed selectively in series relation with said first section and to derive therefrom driving power, of switching means of the pulley and belt type to place said conveyor sections in the aforementioned relations selectively, said belts of said conveyor sections together with the belts of said switching means providing in either case a continuous run having adjacent belts to receive and grip therebetween the articles to be conveyed, said switching means comprising first, second and third pulley shafts for said first, second and third conveyor sections respectively, an adjustably supported pulley shaft and divertible belts driven by said second and third shafts respectively and having running engagement with pulleys on said adjustably supported shaft, and commutatable driving connections for transmitting driving power from said first shaft to said second and third shafts selectively for rotation thereof such that travel of certain of said divertible belts is reversed relative to that of the other of the same.

2. The combination with a plurality of conveyor sections of the pulley and belt type and comprising a driven first section and second and third sections to be placed selectively in series relation with said first section and to derive therefrom driving power, of switching means of the pulley and belt type to place said conveyor sections in the aforementioned relations selectively, said belts of said conveyor sections together with the belts of said switching means providing in either case a continuous run having adjacent belts to receive and grip therebetween the articles to be conveyed, said switching means comprising first, second and third pulley shafts for said first, second and third conveyor sections respectively, an adjustably supported pulley shaft and divertible belts driven by said second and third shafts respectively and having running engagement with pulleys on said adjustably supported shaft, and commutatable driving connections for transmitting driving power from said first shaft to said second and third shafts selectively for rotation thereof such that travel of certain of said divertible belts is reversed relative to that of the other of the same,

3. The combination with a plurality of conveyor sections of the pulley and belt type and comprising a driven first section and second and third sections to be placed selectively in series relation with said first section and to derive therefrom driving power, of switching means of the pulley and belt type to place said conveyor sections in the aforementioned relations selectively, said belts of said conveyor sections together with the belts of said switching means providing in either case a continuous run having adjacent belts to receive and grip therebetween the articles to be conveyed, said switching means comprising first, second and third pulley shafts for said first, second and third conveyor sections respectively, an adjustably supported pulley shaft and divertible belts driven by said second and third shafts respectively and having running engagement with pulleys on said adjustably supported shaft, and commutatable driving connections for transmitting driving power from said first shaft to said second and third shafts selectively for rotation thereof such that travel of certain of said divertible belts is reversed relative to that of the other of the same, said driving connections comprising to afford commutation thereof, gears to be driven selectively by a driving gear common thereto and an adjustable pinion interconnection meshing with said driving gear and with said other gears selectively according to the adjustment of said interconnection.

3. The combination with a plurality of conveyor sections of the pulley and belt type and comprising a driven first section and second and third sections to be placed selectively in series relation with said first section and to derive therefrom driving power, of switching means of the pulley and belt type to place said conveyor sections in the aforementioned relations selectively, said belts of said conveyor sections together with the belts of said switching means providing in either case a continuous run having adjacent belts to receive and grip therebetween the articles to be conveyed, said switching means comprising first, second and third pulley shafts for said first, second and third conveyor sections respectively, an adjustably supported pulley shaft and divertible belts driven by said second and third shafts respectively and having running engagement with pulleys on said adjustably supported shaft, and commutatable driving connections for transmitting driving power from said first shaft to said second and third shafts selectively for rotation thereof such that travel of certain of said divertible belts is reversed relative to that of the other of the same,

third sections to be placed selectively in series relation with said first section and to derive therefrom driving power, of switching means of the pulley and belt type to place said conveyor sections in the aforementioned relations selectively, said belts of said conveyor sections together with the belts of said switching means providing in either case a continuous run having adjacent belts to receive and grip therebetween the articles to be conveyed, said switching means comprising first, second and third pulley shafts for said first, second and third conveyor sections respectively, an adjustably supported pulley shaft and divertible belts driven by said second and third shafts respectively and having running engagement with pulleys on said adjustably supported shaft, selective driving connections for transmitting power from said first shaft to said second shaft or said third shaft, and means for adjusting said adjustable shaft and concurrently effecting corresponding selection of said driving connections.

4. The combination with a plurality of conveyor sections of the pulley and belt type and comprising a driven first section and second and third sections to be placed selectively in series relation with said first section and to derive therefrom driving power, each of said sections having belts to receive and grip therebetween the articles to be conveyed, of switching means of the pulley and belt type to place said conveyor sections in the aforementioned relations selectively, said switching means comprising pulley shafts for said first, second and third conveyor sections, an adjustably supported pulley shaft and divertible belts all having running engagement with pulleys on the last mentioned shaft, and certain of said divertible belts having running engagement with a pulley shaft of said second section while other of the same have running engagement with a pulley shaft of said third section, and commutatable driving connections to transmit to the two last mentioned shafts selectively driving power from a shaft of said first conveyor section, each of said divertible belts having an active and inactive position and in active position serving as an extension belt for its respective conveyor section while said switching means also affords for said conveyor sections extension belts with which said divertible belts coact to grip conveyed articles during transfer from one conveyor section to another.

5. The combination with a plurality of conveyor sections of the pulley and belt type and comprising a driven first section and second and third sections to be placed selectively in series relation with said first section and to derive therefrom driving power, each of said sections having belts to receive and grip therebetween the articles to be conveyed, of switching means of the pulley and belt type to place said conveyor sections in the aforementioned relations selectively, said switching means comprising pulley shafts for said first, second and third conveyor sections, and adjustably supported pulley shaft and divertible belts all having running engagement with pulleys on the last mentioned shaft, and certain of said divertible belts having running engagement with a pulley shaft of said second section while other of the same have running engagement with a pulley shaft of said third section, commutatable driving connections to transmit to the two last mentioned shafts selectively driving power from a shaft of said first conveyor section, each of said divertible belts

75

having an active and an inactive position and in active position serving as an extension belt for its respective conveyor section while said switching means also affords for said conveyor sections extension belts with which said divertible belts coact to grip conveyed articles during transfer from one conveyor section to another, and means to effect concurrently adjustment of said adjustable pulley shaft and corresponding selection of said driving connections.

6. The combination with a plurality of conveyor sections of the pulley and belt type comprising a driven first section, and second and third sections to be placed selectively in series relation with said first section and to derive therefrom driving power, of switching means of the pulley and belt type to place said conveyor sections in the aforementioned relation selectively, said switching means having belts made active thereby selectively according to the conveyor relationship to be established and said belts of said conveyor sections together with the belts of said switching means providing in either case a continuous run having throughout adjacent belts to receive and grip therebetween the articles to be conveyed, and driving connections for transmitting driving power from said first section to the conveyor section placed in series relation therewith and also for drive of belts of said switching means as in either case form part of the continuous run.

7. The combination with a plurality of conveyor sections of the pulley and belt type and comprising a driven first section and second and third sections to be placed selectively in series relation with said first section and to derive therefrom driving power, of switching means of the pulley and belt type to place said conveyor sections in the aforementioned relations selectively, said switching means having belts made active thereby selectively according to the conveyor relationship to be established and said belts of said conveyor sections together with the belts of said switching means providing in either case a continuous run having throughout adjacent belts to receive and grip therebetween the articles to be conveyed, and driving connections for transmitting driving power from said first section to the conveyor section placed in series relation therewith and also for drive of belts of said switching means as in either case form part of the continuous run, said driving connections having commutating means common to the driving connections of said conveyor sections and of belts of said switching means, rendering selection of the last mentioned belts determinable by the selection of conveyor sections.

8. The combination with a plurality of conveyor sections of the pulley and belt type and comprising a driven first section and second and third sections to be placed selectively in series relation with said first section and to derive therefrom driving power, of switching means of the belt and pulley type to place said conveyor sections in the aforementioned relations selectively, said belts of said conveyor sections together with the belts of said switching means providing in either case a continuous run having throughout adjacent belts to receive and grip therebetween the articles to be conveyed, said belts of said switching means comprising divertible belts certain of which shift to inactive position when other of the same shift to active position and vice versa according to the relationship selected for the conveyor sections, and

driving connections for transmitting driving power from said first section to the pulleys of the conveyor section placed in series relation therewith and also for drive of belts of said switching means as in either case form part of the continuous run, said driving connections having commutating means common to the driving connections of said conveyor sections and of the belts of said switching means, rendering selection of the last mentioned belts determinable by the selection of conveyor sections.

9. The combination with a plurality of conveyor sections of the pulley and belt type comprising a driven first section and second and third sections to be placed selectively in series relation with said first section and selectively to derive therefrom driving power, each of said sections having for gripping therebetween articles to be conveyed, first and second belts, of belts interconnecting said first and second conveyor sections and said first and third conveyor sections for continuity therebetween in respect of the first belts of said first and second conveyor sections and the second belts of said first and third conveyor sections, a set of pulleys located between said interconnecting belts and having adjustable support for movement into proximity to said interconnecting belts selectively, pulleys concentric with end pulleys of the second belts of said second and third conveyor sections respectively, belts having running engagement with said adjustable pulleys and dividingly having running engagement with said pulleys concentric with said end pulleys of said second and third conveyor sections for switching, and commutatable driving connections for transmitting driving power from said first section to pulleys of the conveyor section placed in series relation therewith and also for drive of such of said switching belts as also have pulleys concentric with end pulleys of such conveyor section.

10. The combination with a plurality of conveyor sections of the pulley and belt type comprising a driven first section and second and third sections to be placed selectively in series relation with said first section and selectively to derive therefrom driving power, each of said sections having for gripping therebetween articles to be conveyed, first and second belts, of belts interconnecting said first and second conveyor sections and said first and third conveyor sections for continuity therebetween in respect of the first belts of said first and second conveyor sections and the second belts of said first and third conveyor sections, a set of pulleys located between said interconnecting belts and having adjustable support for movement into proximity to said interconnecting belts selectively, pulleys concentric with end pulleys of the second belts of said second and third conveyor sections respectively, belts having running engagement with said adjustable pulleys and dividingly having running engagement with said pulleys concentric with said end pulleys of said second and third conveyor sections for switching, and commutatable driving connections for transmitting driving power from said first section to pulleys of the conveyor section placed in series relation therewith and also for drive of such of said switching belts as also have pulleys concentric with end pulleys of such conveyor section, said driving connections comprising to afford commutation thereof gears to be driven selectively by a driving gear common thereto and an adjustable pinion interconnection meshing with said driving

gear and with said other gears selectively according to the adjustment of said interconnection.

11. The combination with a plurality of conveyor sections of the pulley and belt type comprising a driven first section and second and third sections to be placed selectively in series relation with said first section and to selectively derive therefrom driving power, each of said sections having for gripping therebetween articles to be conveyed, first and second belts, said first and second conveyors being arranged in a substantially straight line relation and said third section being disposed at an angle thereto, of belts driven concurrently with the belts of said first section interconnecting said first and second conveyor sections and said first and third conveyor sections for continuity therebetween in respect of the first belts of said first and second conveyor sections and the second belts of said first and third conveyor sections, a set of pulleys located between said interconnecting belts and having adjustable support for movement into proximity to said interconnecting belts selectively, pulleys concentric with end pulleys of said second and third conveyor sections respectively, belts having running engagement with said adjustable pulleys and dividingly having running engagement with said pulleys concentric with said end pulleys of said second and third sections for switching, and commutatable driving connections for transmitting driving power from said first section to pulleys of the conveyor section placed in series relation therewith and also for drive of such of said switching belts as also have pulleys concentric with such conveyor section, said driving connections comprising to afford commutation thereof gears to be driven selectively by a driving gear common thereto and an adjustable pinion interconnection meshing with said driving gear and with said other gears selectively according to the adjustment of said interconnection.

12. The combination with a plurality of conveyor sections of the pulley and belt type comprising a driven first section and second and third sections to be placed selectively in series relation with said first section and to selectively derive therefrom driving power, each of said sections having for gripping therebetween articles to be conveyed, first and second belts, said first and second conveyors being arranged in a substantially straight line relation and said third section being disposed at an angle thereto, of belts driven concurrently with the belts of said first section interconnecting said first and second conveyor sections and said first and third conveyor sections for continuity therebetween in respect of the first belts of said first and second conveyor sections and the second belts of said first and third conveyor sections, a set of pulleys located between said interconnecting belts and having adjustable support for movement into proximity to said interconnecting belts selectively, pulleys concentric with end pulleys of said second and third conveyor sections respectively, belts having running engagement with said adjustable pulleys and dividingly having running engagement with said pulleys concentric with said end pulleys of said second and third sections for switching, and commutatable driving connections for transmitting driving power from said first section to pulleys of the conveyor section placed in series relation therewith and also for drive of such of said switching belts as also have pulleys concentric with such conveyor section, said driving connections comprising to afford commutation thereof gears to be driven selectively by a driving gear

11

common thereto and an adjustable pinion interconnection meshing with said driving gear and with said other gears selectively according to the adjustment of said interconnection, and a section joint affording support for pulleys of said second conveyor section and comprising a pulley element for engagement by such of said switching belts as extend from said third conveyor section to said adjustable pulley set.

13. The combination with a plurality of conveyor sections of the pulley and belt type comprising a driven first section and second and third sections to be placed in series relation with said first section selectively and to derive therefrom driving power, of switching means of the pulley and belt type to place the conveyor sections in the aforementioned relations selectively, commutable driving connections having chains for transmitting driving power from said first section to pulleys of said switching means and of the conveyor section placed in series relation with said first conveyor section, said driving connections comprising to afford commutation thereof

gears to be driven selectively by a driving gear common thereto and an adjustable pinion interconnection meshing with said driving gear and with said other gears selectively according to the adjustment of said interconnection, and two supporting frames which afford support for the aforesaid commutating parts of said driving connections and also for pulleys of said conveyor sections and switching means, to afford two units through the medium of which the said three conveyor sections may be coordinated as afore-described by mere addition of the aforementioned belts and driving chains.

KENNETH H. HANSEN.
